SPATULA

Frank M. Jackson, San Francisco, Calif., assignor to Dist-
mark, Inc., San Francisco, Calif., a corporation of
California

Filed Nov. 12, 1964, Ser. No. 82,551

Term of patent 3½ years

(Cl. D44—29)

F i g. 1

F i g. 2

F i g. 3

FIGURE 1 is a top plan view of the spatula showing my new design.

FIGURE 2 is a side elevational view of the spatula.

FIGURE 3 is a bottom plan view of the spatula.

The essential feature of my design resides in the specific perforation pattern shown on the blade portion of a spatula having the configuration disclosed.

I claim:

The ornamental design for the spatula, as shown and described.
